CLAIM

The ornamental design for an electronic sphygmomanometer, as shown and described.

DESCRIPTION

FIG. 1 is a front and top perspective view of an electronic sphygmomanometer, showing my new design;

FIG. 2 is a rear and bottom perspective view thereof;

FIG. 3 is a front elevation view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of the portion, labeled '9' of FIG. 2.

The broken lines depict portions of the electronic sphygmomanometer in which the design is embodied that form no part of the claimed design.
